UNITED STATES PATENT OFFICE

164,139

WINDOW VENTILATOR

Ford Se Bastian, Chicago, Ill., assignor to Chicago
Electric Manufacturing Company, Chicago, Ill.,
a corporation of Illinois

Application December 20, 1949, Serial No. 6,736

Term of patent 7 years

(Cl. D62—4)

To all whom it may concern:

Be it known that I, Ford Se Bastian, a citizen of the United States, residing in Chicago, Cook County, State of Illinois, have invented a new, original, and ornamental Design for Window Ventilator, of which the following is a specification, reference being had to the accompanying drawing, forming a part thereof.

Fig. 1 is a front perspective view of a window ventilator, showing my design;

Fig. 2 is a top plan view thereof;

Fig. 3 is an end elevational view thereof.

Fig. 4 is a reduced fragmentary rear view showing the fan and rear guard.

I claim:

The ornamental design for a window ventilator, as shown.

FORD SE BASTIAN.
